(57) **CLAIM**

The ornamental design for a borescope, as shown and described.

DESCRIPTION

FIG. 1 is a front perspective view of a borescope according to the present invention.

FIG. 2 is a front view of the borescope of FIG. 1, on an enlarged scale.

FIG. 3 is a rear view of the borescope of FIG. 1, on an enlarged scale.

FIG. 4 is a left side view of the borescope of FIG. 1.

FIG. 5 is a right side view of the borescope of FIG. 1.

FIG. 6 is a top view of the borescope of FIG. 1; and,

FIG. 7 is a bottom view of the borescope of FIG. 1.

The broken line showing a part of the borescope is for the purpose of illustrating a portion of the borescope that forms no part of the claimed design.

The dash-dash broken line represents a symbolic break within the borescope. The appearance of any portion of the article between the symbolic break forms no part of the claimed design.
